UNITED STATES PATENT OFFICE.

EDWIN DARBY, OF WATERLOO, IOWA, ASSIGNOR OF ONE-HALF TO WILLIAM M. DARBY, OF IOWA CITY, IOWA.

OIL-BURNER.

1,360,898.

Specification of Letters Patent.

Patented Nov. 30, 1920.

Application filed December 29, 1919. Serial No. 348,253.

To all whom it may concern:

Be it known that I, EDWIN DARBY, a citizen of the United States, residing at Waterloo, in the county of Blackhawk and State of Iowa, have invented certain new and useful Improvements in Oil-Burners, of which the following is a specification.

This invention relates to a liquid fuel vaporizer and heater designed for use in connection with stoves, of both heating and cooking type, farm tank heaters and other forms of stove or furnace structure.

As the invention relates to the construction of the burner, vaporizing coil, and connected parts, I have not shown or described the stove or tank heater, as the construction of these would depend on the make of stove or tank heater employed, and is outside of the present invention.

20 The invention consists in the novel features of construction hereinafter described, pointed out in the claims and shown in the accompanying drawings, in which:—

Figure 1 is a plan view partly in section. 25 Fig. 2 is a section on the line 2—2 of Fig. 1.

In the drawing 1 is a suitable base having the form of a shallow tray and providing a drip pan 2. The base is centrally cut out as 30 at 3, this cut out portion being inclosed by a vertical wall 4, spaced from the edge of the opening 3, and which forms the inner wall of the drip pan 2. Radial ribs 5 extend transversely across the drip pan and 35 are preferably three in number. These ribs are higher than the side walls of the pan and at their inner ends are cut out to form shoulders 6, said shoulders being in the horizontal plane of the drip pan walls, including the inner wall 4. A dome or cap 7, opening 40 downwardly is supported on the shoulders 6. Resting on the marginal portions of the opening 3 is a double walled burner 8, the inner wall being perforated as at 8^s, the air space between the walls being closed at 45 the bottom and open at the top. The burner extends upwardly into the dome 7 and affords communication through the opening 3 with the dome. As the dome is 50 elevated by the shoulders 6 it also communicates with the drip pan 2.

An oil feed pipe 9 leads from any suitable source of supply and is bent in the form of coils 9^a about the dome 7, the coils resting 55 on the ribs 5, and the pipe is then bent

downwardly and upwardly into alinement with the opening 3 terminating in a discharge orifice 9^b. Where it passes through the drip pan it is inclosed by a boss 10. A supplemental feed pipe 11 depends over the 60 drip pan 2 and supplies said pan with oil for ignition purposes, the pan being supplied with the usual asbestos wick, or with any suitable oil absorbing material.

A depending flange 12 forms a support 65 for the supply pipe at a point below the burner.

A heat retaining plate 13 is placed over the coils 9^a.

Suitable valves, not shown, are employed 70 in the pipes 9 and 11, and are located at any convenient point, and a supply reservoir, not shown, may be located where most convenient, or as considerations of safety may dictate.

The oil vaporized in the coils will be discharged through the orifice 9^b into the burner 8 which also serves as a mixer and the flames will spread through the dome and out from under its lower edge.

75 What I claim is:—

1. An oil burner comprising a base forming a drip pan, and having a central opening, radial ribs extending across said pan, the pan having outer and inner walls, a 80 downwardly open dome resting on said ribs, a burner mounted on the base in alinement with the opening and extending upwardly into said dome, and a supply pipe, a portion of said pipe being coiled about the dome 85 and resting on said ribs, as and for the purpose set forth.

2. An oil burner comprising a base forming a drip pan with inner and outer walls, the central portion of the base within the 90 inner wall being cut out, a burner mounted on the marginal portions of said cut out portion of the base, and retained in position by the inner drip pan wall, transverse ribs extending from wall to wall of the pan and 95 having shoulders formed on their inner end portions, a dome mounted on said shoulders, means for supplying oil to the drip pan, and a supply pipe adapted to discharge an oil vapor into said burner through the 100 cut out portion of the base, a portion of said pipe being coiled about the dome and supported by said ribs.

3. In an oil burner, a drip pan, a dome supported above said pan, said pan having 110

an inner wall and being centrally cut out within said wall, a supply pipe partially coiled about the dome and above the pan and discharging through said cut out portion, 5 and a double-walled burner mounted within the inner wall of the drip pan and affording communication between the cut out portion

of the pan and the dome, the inner wall of the burner being perforated, and the air space between the burner walls opening upwardly into the dome. 10

In testimony whereof I affix my signature.

EDWIN DARBY.
